FURNITURE LEG FOOT OR THE LIKE

David Chapman, Chicago, Ill., and Richard G. Reineman, Muskegon, Mich., assignors to The Brunswick-Balke-Collender Company

Application August 31, 1953, Serial No. 26,629

Term of patent 14 years

(Cl. D33—1)

Fig. 1.

Fig. 2.

Fig. 3.

To all whom it may concern:

Be it known that we, David Chapman and Richard G. Reineman, citizens of the United States, residing at Chicago, in the county of Cook, State of Illinois, and Muskegon, in the county of Muskegon, State of Michigan, respectively, have invented a new, original, and ornamental Design for a Furniture Leg Foot or the like, of which the following is a specification, reference being had to the accompanying drawing, forming a part thereof.

In the drawing:

Fig. 1 is a front elevational view of a furniture leg foot or the like embodying our new design;

Fig. 2 is a side elevational view thereof; and

Fig. 3 is a top plan view thereof.

We claim:

The ornamental design for a furniture leg foot or the like, as shown.
